Ex

NO. 11,266

JUNE 24, 1879

UNITED STATES PATENT OFFICE.

GEORGE S. BARKENTIN, OF HARTFORD, ASSIGNOR TO P. & F. CORBIN, OF NEW BRITAIN, CONNECTICUT.

DESIGN FOR LOCK-CASES.

Specification forming part of Design No. **11,266**, dated June 24, 1879; application filed May 31, 1879.
[Term of patent 7 years.]

To all whom it may concern:

Be it known that I, GEORGE SLATER BARKENTIN, of the city of Hartford, in the county of Hartford and State of Connecticut, have originated and produced a new and original Design for Lock-Case, of which the following is a full, clear, and exact description, reference being had to the accompanying engraving, making part of this specification.

My design relates to the ornamentation of the two sides of the lock-case, one of which is shown in the accompanying engraving. Upon the nosing A is a zigzag band, of which each right-hand division incloses a pointed leaf crossed by vertical and horizontal lines, and each left-hand division incloses a sunken leaflet.

The borders *b b b b* are formed of sunken

panels with dotted ground, within which are rows of quarterfoils in relief. The inner borders, *c c c c*, consist of incised lines, forming dentils. The surface inclosed by the border is preferably ornamented with perpendicular flutes, as shown

I claim as my invention—

The design for lock-case, consisting of the zigzag band upon the nosing A, and the borders *b b b b* and *c c c c*, inclosing flutes, substantially as shown and described.

Signed by me this 28th day of May, A. D. 1879.

GEORGE SLATER BARKENTIN.

Witnesses:

CHARLES PECK,
CHAS. F. CORBIN.
